UNITED STATES PATENT OFFICE.

WILLIAM S. ELLIOT, OF NORTHAMPTON, MASSACHUSETTS, ASSIGNOR, BY MESNE ASSIGNMENTS, TO UNITED FAST COLOR EYELET COMPANY, OF PORTLAND, MAINE, A CORPORATION OF MAINE.

SETTING-DIE.

No. 833,515.

Specification of Letters Patent.

Patented Oct. 16, 1906.

Application filed December 7, 1904. Serial No. 235,810.

To all whom it may concern:

Be it known that I, WILLIAM S. ELLIOT, a citizen of the United States, residing at a Northampton, county of Hampshire, State 5 of Massachusetts, have invented a certain new and useful Improvement in Setting-Dies, of which the following is a specification, reference being had therein to the accompanying drawings.

10 My invention has for its object an improved die for use in setting eyelets and like articles which shall operate without the defects found in such dies as heretofore constructed.

15 My invention will be fully understood from the following description and the accompanying drawings, and the novel features thereof are pointed out and clearly defined in the claims at the end of this specification.

20 In the accompanying drawings, Figure 1 is a vertical section of an eyelet-set and its co-operating anvil, the said set embodying my invention. Fig. 2 is a modification herein-after referred to.

25 My invention relates more particularly to dies for setting eyelets and similar articles provided with tops of celluloid or other plastic material molded thereon or which have their tops covered with a finishing layer or

30 coating of plastic material, enamel, or the like. It has been found that in setting these eyelets by means of setting-dies of any of the well-known kinds the molded top or finishing layer is apt to be cracked or broken, and this

35 is especially the case if the said top is ornamented or roughened or has formed thereon projecting figures or the like. By the employment of a setting-die embodying my invention I am enabled to reduce to a mini-

40 mum the number of such eyelets or similar articles broken during the setting operation. My improved die is also less likely to disfigure the ornamentation, if any there be, on the top of the eyelet.

45 Referring to the drawings, A is a setting-die of usual form and construction and having a retractable spindle B of usual construction and operation. The co-operating anvil is shown at C and is provided with the usual

50 post or projection, which when the eyelet is being set projects within the barrel thereof. The set and anvil and connected parts are usually made from steel. The hollowed or rounded face 2 of the set A corresponds in

shape with the top of the eyelet, the said set 55 having an annular concavity which substantially fits the annular curved top of the eyelet.

In applying my invention to a set I make an annular groove or recess 3 in the face of the set at the bottom of the annular concavity therein and fit tightly within the same a ring or cushion 4, of yielding or elastic material, preferably rubber. The free or outer face of this rubber ring 4 should extend, as 60 shown, slightly above the adjoining metal faces of the concavity, so that when the set is brought in contact with the top of the eyelet and is pressed against the same in the act of setting the eyelet the rubber ring 4 will first 70 bear on the top of the eyelet and will be compressed as the pressure is applied until the top of the eyelet also bears on the adjoining metal portions of the said face 2 of the set. If there are any raised portions or projections 75 on the top of the eyelet, they will sink into and be accommodated by the yielding ring or cushion 4, of rubber, and the setting pressure will be uniformly applied. As will 80 be clear, by varying the softness or yielding quality of the rubber employed fine or delicate projections on the top may be protected from breakage. It will be further understood that I may vary the width of the rubber portion of the face of the set as desired for eyelets 85 or like articles of varying size and also for eyelets or the like of the same size, but having projections or the like of varying sizes thereon. I do not desire to limit myself, however, in these particulars. In practice, 90 however, I have found it desirable to have a portion of the face of the set, preferably on each side of the rubber ring, of metal, which will bear upon the top of the eyelet when the setting pressure has increased sufficiently to 95 compress the rubber.

In the modification shown, Fig. 2, I omit the rubber ring, but cut away the concave face of the setting-die, as shown at 6. This keeps the cut-away portion of the die 100 wholly out of contact with any projection or the like on the top of the eyelet, but does not operate to distribute the setting pressure uniformly, and therefore, while affording some of the advantages of the preferred embodiment of my invention heretofore described, I have found it much less desirable in practice than the said preferred form.

What I claim is—

1. A setting-die having an annular recess in the face thereof and a cushion of yielding material in the said recess.
- 5 2. A setting-die having an annular recess in the face thereof and having in said annular recess an annular cushion of yielding material.
- 10 3. A setting-die for eyelets having a ring of rubber in the face thereof, said ring of rubber when not compressed projecting slightly above the adjacent portions of the face of the die.
- 15 4. In an eyeleting-machine, an upsetting-die, and a pressure-die arranged to sustain the pressure of the upsetting-die which is transmitted through an eyelet, said pressure-die having a pressure-sustaining surface constructed to contact with the face of an eyelet-head without contacting with a raised portion on said face.
- 20 5. An eyelet-setting die having surfaces for exerting pressure upon the outer part and the inside of the head of an eyelet and constructed between said surfaces to receive a raised portion on the head of the eyelet and prevent it from being subjected to excessive pressure during the operation of setting the eyelet.
- 25 30 6. In an eyeleting-machine, an upsetting-die, and a pressure-die arranged to sustain the pressure of said upsetting-die and provided with a surface which is recessed to receive a raised portion on an eyelet-head.
- 35 7. In an eyeleting-machine, an upsetting-die, and a pressure-die provided with two

surfaces which are spaced apart and arranged to sustain the pressure of said upsetting-die.

8. In an eyeleting-machine, an upsetting-die and a pressure-die, the latter being provided with an annular recess, as and for the purpose described.

9. An eyelet-setting die having an engaging surface for exerting pressure upon the head of an eyelet and provided with a recess for receiving a raised portion on the head of the eyelet, said recess being of greater dimensions than said raised portion.

10. An eyelet-setting die provided with an engaging surface conforming to the outer part of the head of an eyelet and an engaging surface conforming to the inside of the head of the eyelet and having a recess intermediate said surfaces for receiving raised portions on the head of the eyelet to prevent them from being subjected to excessive pressure during the operation of setting the eyelet.

11. An eyelet-setting die having annular engaging surfaces substantially concave in cross-section for applying pressure to the head of an eyelet, and an annular recess for receiving raised portions on the head of the eyelet, said recess being of greater dimensions than said raised portions to prevent them from being subjected to pressure during the operation of setting the eyelet.

In testimony whereof I affix my signature in presence of two witnesses.

WILLIAM S. ELLIOT.
